CLAIM

The ornamental design for an LED light, as shown and described.

DESCRIPTION

FIG. 1 is a perspective view of the LED light showing my new design;

FIG. 2 is a front elevational view thereof;

FIG. 3 is a rear elevational view thereof;

FIG. 4 is a left-side view thereof;

FIG. 5 is a right-side view thereof;

FIG. 6 is a top plan view thereof;

FIG. 7 is a bottom plan view thereof;

FIG. 8 is an enlarged front elevational view of the LED light shown in FIG. 2;

FIG. 9 is an enlarged rear elevational view of the LED light shown in FIG. 3; and,

FIG. 10 is an enlarged bottom plan view of the LED light shown in FIG. 7.

The broken lines illustrate portions of the LED light which form no part of the claimed design.

The dash-dot-dash-dot broken lines are boundary lines and define the bounds of the claimed design. The claimed design extends to the boundary lines but does not include the boundary lines.

The break lines shown in FIG. 10 have been included in order to show the design at a large scale and the design is understood to continue uniformly between the break lines and be of the length shown in FIG. 7.
